(57) **CLAIM**

The ornamental design for a cat toy, as shown and described.

DESCRIPTION

FIG. 1 is a perspective view of the cat toy showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a partial enlarged view of portion 8 in FIG. 1; and, FIG. 9 is a partial enlarged view of portion 9 in FIG. 2.

The dash broken lines illustrate portions of the cat toy that form no part of the claimed design; and the dot-dash broken lines represent the boundary of the enlarged views and form no part of the claimed design.
